SERVICE DEVICE

Edward A. Taub, North Bergen, N. J., assignor to
 Gibraltar Corrugated Paper Co. Inc., North
 Bergen, N. J., a corporation of New Jersey

Application December 26, 1933, Serial No. 703,991

2 Claims. (Cl. 224—48)

This invention relates to improvements in service devices and has more particular relation to bottle carrying devices for use in oil dispensing stations or the like.

5 The object of the invention is to provide a collapsible bottle carrying device that may be readily erected and be capable of conveniently carrying a plurality of bottles of oil, milk or the like, by hand and with the bottles occupying compartments.

10 A further object of the invention is to provide a collapsible bottle-carrying device constructed of paper board and so constructed that it may be instantly and permanently assembled by an unskilled person and provide a protective carrier for bottles of oil, milk or other liquids.

15 Another object of the invention is to provide a collapsible hand carrier for bottles in which the weight is equally distributed from a common 20 point of suspension so that there will be no tendency of the carrier to tip one way or the other when being carried.

25 The invention also has other objects, all of which will be hereafter more particularly set forth and claimed.

In the accompanying drawings:

Figure 1 represents a top plan view of the devices embodying my invention, partly in dotted lines and containing two bottles of oil provided 30 with dispensing funnels.

Figure 2 represents a front elevation of the same.

Figure 3 represents a top plan view, partly 35 broken away, of a single piece of corrugated paper board, from which the carrier is constructed.

Figure 4 represents a perspective view of a modern oil container can, and

Figure 5 represents a side elevation, partly 40 broken away, of one of the detachable funnels and can openers.

It has heretofore been the practice in automobile gasoline and oil service stations to provide carriers for the oil bottles constructed of metal or wood. Such carriers are manufactured complete 45 at the factory and are shipped in their assembled condition which results in their occupying considerable space and costing considerably more for such shipping than would a "knock-down" carrier which may be shipped flat.

50 With this thought in mind, the present invention is designed to construct a rigid and well balanced hand carrier for the use of the attendants at oiling stations which has a minimum weight and may be shipped in a collapsed condition in which it occupies a flat plane with one carrier piled upon the other, but be capable at the same time of being instantly erected by an unskilled person to provide a perfect oil carrier of the lightest possible construction, and containing 55 suitable advertising matter printed thereon such

as usually printed, with a minimum expense, upon paper.

By reference to Figure 3, it will be seen that 21 represents the bottom of the carrier, 24 and 25 the front and back of the same, 34 and 35 the opposite sides of the roof or top of the carrier and 22 and 23 the ends of the carrier. 5

As the carrier is constructed of a single piece of corrugated cardboard of any desired type, scored lines 1, 2, 3 and 4 are provided between the bottom, 10 the front and back and the ends so that the board may be doubled at these points to erect the carrier upon the base 21 in the form of a container.

This container, in the present instance, is printed exteriorly to represent a small service station or house having windows and doors therein, and a red tile roof. The windows 40 are formed in the front and back walls respectively and so arranged as to permit the contents of the oil bottle back of them to be examined. This 20 inspection of the oil bottle is particularly desirable as heavy and light grades of oil may be carried in the same carrier and the attendant will wish to know which bottle he is lifting from the carrier before withdrawing it. 25

Further, after the attendant has emptied one bottle and placed it back within the carrier, if his attention is withdrawn for a minute, he will not have to lift the empty bottle to ascertain which is the full bottle remaining in the carrier. 30 These windows 40 thus serve a real function in carrying out the invention as well as forming a part of the design of the building represented by the carrier.

As it has been the practice of oil companies to 35 adopt a certain style of building for their service stations so that the public will know a certain station by the type of building it has, this policy has been further carried out by constructing the carrier in imitation of the type of building desired. Thus a purchaser of oil at a station will realize at once by the type of building illustrated on the carrier what make of oil is contained within the carrier. This peculiar characteristic of the carrier associated with the oil 45 company which is manufacturing a particular kind of oil, is very desirable where a service station is of a general character and is handling many different kinds of oil and gasoline. In such instances, not only the attendant, but the 50 customer, will know that he is being served with oil of the particular type that he has ordered and not with some other type that he does not desire.

In order to hold the carrier erected in the form in which it is used, each of the ends 22 and 23 55 is provided on opposite sides with extension flaps 26, 38, 28 and 32 and with connected locking and partition flaps 27, 31, 29 and 33; scored lines 9, 10, 11 and 12 being formed between the respective flaps and scored lines 5, 6, 7 and 8 between the 60

flaps and the ends. Slots 27', 29', 31' and 33' are formed in the front and back walls 24 and 25 and when the carrier is erected and the ends 22 and 23 moved into a vertical position and the flaps 26, 30, 28 and 32 bent along the front and rear walls, the flaps 27, 31, 29 and 33 are inserted through these slots and hold the entire device in its erected position.

By reference to Figure 1, it will be seen that these flaps extend towards each other within the carrier and form partition walls that hold the bottle securely in position against sliding about or "tipping" even though the carrier is given very rough usage.

15 The roof sections 34 and 35 are scored as at 13 and 14 where they join the front and back walls and each of these sections is provided with a "hand hold" flap 36 and 37 formed respectively with finger apertures 38 and 39, scored lines 15 20 and 16 being formed between the roof sections and these flaps. When the two "hand hold" flaps are brought together they hold the roof sections 34 and 35 in position as the two flaps lying side by side as shown in Figure 1 constitute the 25 "peak" of the roof.

A modern practice has grown up in the service of oil at oil stations of dispensing the oil to customers from sealed cans to prevent inferior oils from being substituted for high grade oils. Such 30 a can is illustrated in Figure 4 and in order to open this can and pour its contents into the engine of an automobile, a funnel 47, such as is shown in Figure 5, is provided. This funnel internally is provided with puncturing points 48. The funnel 35 is inverted and forced down on top of the can 46 to give a slight movement which punctures the thin top of the can. The funnel and can together are then inverted and the contents of the can poured through the funnel into the engine. Such cans with the funnels on top and 40 ready for service, may be carried in the present carrier, just as the glass bottle with a funnel on it would be carried. The attendant, however, in this instance, must first disclose to the purchaser the unopened can. If this is desired, the cans alone, without the funnels, might be carried in the carrier and viewed through the windows 45 40, and the funnel 47 inserted after withdrawing the can from the carrier.

50 While this invention has been described as particularly applicable to the servicing of oil at oil stations, it will, of course, be understood that the carrier, with equal facility, may be used for the delivery of milk bottles, as the protection of such 55 bottles is desired. These bottles are held separated and prevented from violently striking each other, just as would the oil bottles previously described.

The peculiar tapered construction of the top 60 sections 34 and 35 results in the top of the carrier being only partly enclosed so that the tops of the bottles and funnels may project through the top and thus reduce the size of the holder necessary to contain bottles and funnels of a 65 given height and allow for the ready removal of the bottles.

This structure further prevents the "tipping" of the funnel or the top of the bottle and holds it in position on three sides, as shown in Figure 1.

70 Bottles in a carrier, as herein described, are so well protected against breakage that the carrier may be handled with extreme roughness without the bottle striking anything hard enough to break it and without any possibility of the bottles 75 coming together in such a way as to break them,

This is particularly true as the whole structure is constructed of corrugated board which is soft enough to absorb any shock of the bottle striking against the walls of the carrier.

It will be observed that by the peculiar arrangement of the so-called windows in the back and in corresponding positions in the front of the carrier, the oil in the containers may be readily examined while in the containers by looking through the oil from the front to the back. This is practically the only true way of examining the oil 10 as to its quality, as otherwise the light will not be correct to look through the oil.

If the light were to come from one side only, 15 as it would with a single window, this light would be reflected from the oil and under such conditions all oil seems alike or of a greenish tint and its quality is concealed. It thus becomes essential to look entirely through the oil in order to judge of its quality.

It will be understood that one of the best known tests of the grade and quality of oil is made by looking through the oil while it is contained in a transparent container.

The present holder for oil bottles is so constructed that the windows in the front and back walls of the holder or carrier are in alignment and therefore when the carrier is held elevated, the attendant can look through the oil from front to back and therefore determine its particular grade or its color or quality.

This is true of oil only when it may be examined by looking entirely through it. When oil is viewed from the front with simply reflected light coming from the front, it has a peculiar dark opaque appearance by which its grade or quality cannot be judged. A holder having windows in the front only would not be effective with oil as with applicant's present holder and carrier.

What I claim is:

1. A collapsible bottle display rack formed from a single blank having a bottom, front, rear and end walls, inclined tapered tops extending from the edges of the front and rear walls and having matched handles which with the tops form a central support and closure for the rack, the end walls having no top portion, the tops when brought together forming a triangular opening at each end through which the upper portion of the container extends, the sides of the top adapted to hold the container in position when the handles are together and permitting withdrawal of the containers upon the separation of the handles.

2. A collapsible bottle display rack formed from a single blank having a bottom, front, rear and end walls, inclined tapered tops extending from the edges of the front and rear walls and having matched handles which with the tops form a central support and closure for the rack, the end walls having no top portion, the tops when brought together forming a triangular opening at each end through which the upper portion of the container extends, the sides of the top adapted to hold the container in position when the handles are together and permitting withdrawal of the containers upon the separation of the handles, tabs securing the end walls to the front and rear walls, said tabs extending through said walls to form retainers for receptacles, said tabs and tops when in closed position forming retaining means against displacement of receptacles in said rack.
